UNITED STATES PATENT OFFICE.

JOSEPH B. HOLDEN, OF SYRACUSE, NEW YORK, ASSIGNOR TO REMINGTON TYPEWRITER COMPANY, OF ILION, NEW YORK, A CORPORATION OF NEW YORK.

TYPEWRITING MACHINE.

Application filed April 16, 1923. Serial No. 632,235.

To all whom it may concern:

Be it known that I, JOSEPH B. HOLDEN, citizen of the United States, and resident of Syracuse, in the county of Onondaga and State of New York, have invented certain new and useful Improvements in Typewriting Machines, of which the following is a specification.

My invention relates to typewriting or like machines, and more particularly to means for clamping labels or cards to the surface of the platen.

The main object of the invention, generally stated, is to provide simple and efficient means of the character specified which may be easily assembled on the platen; which may be manufactured at small cost, and which does not interfere with the use of the machine for ordinary work when the clamping means are not to be used.

To the above and other ends which will hereinafter appear, my invention consists in the features of construction, arrangements of parts and combinations of devices set forth in the following description and particularly pointed out in the appended claims.

In the accompanying drawings wherein like reference characters indicate corresponding parts in the different views,

Figure 1 is an enlarged longitudinal sectional view of a platen equipped with the clamping means of my invention; the section being taken on the line 1—1 of Figure 2 and looking in the direction of the arrows at said line.

Figure 2 is a transverse sectional view of the same taken on the line 2—2 of Figure 1 and looking in the direction of the arrows at said line.

Figure 3 is a right-hand end view of the platen with parts broken away.

Figure 4 is a fragmentary face view of the platen showing a label clamped thereto.

Figure 5 is a detail fragmentary sectional view taken on the line 5—5 of Figure 3 and looking in the direction of the arrows at said line; the view showing the clamp controlling lever and some of the associated parts.

Figure 6 is an end view of the clamp controlling lever; and

Figure 7 is a detail fragmentary perspective view of the clamp supporting rod and one of the clamping fingers carried thereby.

I have shown the devices of my invention in the present instance employed on the platen of a Remington portable machine, though they are capable of application to the platens of typewriting and like machines generally, and without interfering with the employment of the machines for ordinary purposes when the clamping means are not in use.

The cylindrical platen is designated as a whole by the reference numeral 1, and comprises an outer shell 2 of rubber or like material, and the outer face of which forms a contact surface which supports the work sheet and on which a label or card is adapted to be clamped. The shell 2 is fixed to an inner shell 3, preferably made of metal and perforated at different points in the length thereof, as indicated at 4. The shell 3 at one end has a platen head 5 secured thereto by screws 6, whereas a second platen head 7 is secured to the opposite end of the shell 3 by screws 8. The platen head 5 has a central bearing opening 9 to receive the usual platen shaft or spindle (not shown) that also is received in a central bearing opening 10 in a capped bushing 11 secured by screws 12 to the platen head 7. A line spacing wheel 13 in the present instance is secured by screws 14 to the platen head 5. An off-centered tapered bearing opening 15, circular in cross-section, is formed in the platen head 5, and the axis of such opening extends parallel with the axis of the platen.

A cylindrical clamp supporting rod 16 has one end seated and supported in the bearing opening 15. This rod is maintained wholly within the platen and extends longitudinally thereof substantially parallel with the axis of the platen. The opposite or free end portion of the rod is preferably slabbed off on one side to provide a half-round reduced end portion 17. This reduced end portion conforms substantially in cross section to a seat 18 (see Fig. 6) of a socket 19 provided at the inner end in a sheet metal controlling lever 20, shown in detail in Figs. 5 and 6. The end 17 of the rod is somewhat loosely seated in the socket 19 to enable the rod and lever 20 to assume varying angular relations, and permit such parts to be readily assembled and enable a detachment of the lever from the rod to be effected when desired. The con-

nection between the rod and lever is such, however, that the lever supports the free end of the rod, and controls its lateral swinging movement around the point of support in the bearing opening 15 in the left-hand platen head 5; such movement of the rod being permitted by the tapering walls of the opening 15 in which the rod is seated. The lever 20 is received in a bearing slot 21 in the right-hand platen head 7, and in an inwardly projecting lug or extension 22 on said head, and is fulcrumed thereon on a transverse pivot pin 23 that crosses said slot. The lever 20 extends from the inside of the platen to the outside thereof near one end, passing through the slot 21 and through a registering open-ended slot 24 in the shell 3. The outer end of the lever 20 is provided with a finger piece 25, which preferably does not extend beyond an extension of the outer surface of the platen. The lever and its finger piece, therefore, will not interfere with a work sheet which may overlap the right-hand end of the platen. A depending pin 26 is riveted to the under side of the finger piece 25, and extends into a coiled expansion spring 27 received in an opening 28 in the platen head 7; the spring bearing at its inner end against the bushing 11 which forms the bottom wall of the opening 28.

A groove 29 is provided in, and extends longitudinally of, the rod 16 and in this groove is seated and secured the foot piece 30 of each of the wire clamping fingers. Each clamping finger is fixed to the rod as, for example, by soldering its foot piece in the groove 29. Each clamping finger is formed with an outwardly extending stem 31 that is bent forward at right angles to the length of the stem at the outer free end portion thereof, to form a clamping or engaging member 32. Any desired number of clamping fingers may be provided, three being shown in the present instance near the right-hand end portion of the platen, as shown in Fig. 4. Each clamping finger extends through an opening 4 in the inner shell 3 and through a rectangular registering opening 33 in the outer shell 2. Each opening 33 is of such dimension in cross section, as to receive the associated clamping member 32 and permit it to move therethrough, but substantially fill the opening 55 at the surface of the platen when the part 32 is positioned in its opening, as indicated in Figs. 1 and 2. In the normal position of the parts, shown in these figures, the outer surface of each part 32 forms substantially a continuation of the outer surface of the platen, and forms a support for a work sheet resting on the platen. I prefer to arrange the engaging members 32 on a line extending longitudinally of the platen 60 between two adjacent teeth 13^a of the line

spacing wheel. In this manner, the parts 32 are brought between printing lines, and when not in use are situated beneath the work sheet between two adjacent lines of writing, and are never brought directly under a line of writing on the sheet during the control of the platen by its line spacing mechanism. It will be understood, therefore, that when the clamp is not in use, it does not interfere in any manner with the use of the machine for writing in the ordinary manner on a work sheet.

In order to use the clamp it is merely necessary to depress the finger piece 25 against the force of the spring 27. The effect of this is to move the inner end of the lever outwardly away from the axis of the platen, and swing the rod 16 laterally by pivotal movement around the point of its support. This outward swinging movement of the rod causes the engaging members 32 of the clamping fingers to be moved outwardly beyond the outer surface of the platen. While the parts are maintained in this position, the leading edge of the label or card 34 is introduced beneath the members 32, and the operator releases the finger piece or key 25. The spring 27 tends to return the parts to normal position and such movement of the parts brings the members 32 into clamping engagement with the leading edge portion of the label as shown in Fig. 4, thus holding the label on the platen to turn therewith. When the label is written, the operator depresses the key 25, releasing the clamping fingers and enabling the label to be detached.

In assembling the parts the rod 16 with the clamping fingers fixed thereon is introduced lengthwise into the platen; introducing the left-hand end of the rod into the bearing opening 15 by such movement. The rod is then swung laterally in its bearing opening 15, projecting the clamping fingers through their respective openings 4 and 33 in the platen. While the rod is maintained relatively to the platen in substantially the position shown in Fig. 1, the right-hand platen head is introduced and secured in position while the lever 20 is held thereon substantially in the position shown. In assembling the parts in this manner, the free end of the rod 16 will enter the socket 19. The right-hand end of the rod 16 is rounded so that it may more readily find the center itself in the socket 19 when the platen head 7 is introduced into position on the platen. In placing the head 7 in position as described, the key carrying stem 20^a of the lever is introduced into the open-ended slot 24 in the shell 3, through which slot said stem projects when the parts are assembled, as indicated in Figs. 3 and 5. As the head 7 is moved home into assembled position, the upper edge 20^b of the lever 20 to the right

of its fulcrum, is brought to bear against the inner surface of the shell 3, as indicated at 3^a in Fig. 5. The shell 3 at this point therefore acts as a stop to limit the motion 5 of the lever under the action of its spring 27, and normally maintains the parts in the position shown in Figs. 1 and 5.

From the foregoing description it will be understood that I have provided simple, inexpensive and effective label or card clamping means that may be readily assembled on the platen, and which when not in use does not interfere with the employment of the machine for ordinary work.

15 It will be observed, moreover, that by merely removing the shaft or spindle of the ordinary platen, such platen may be readily replaced by one equipped with the label clamping means of my invention; such 20 replacement being easily and quickly effected.

Various changes may be made without departing from my invention as it is defined in the accompanying claims.

25 What I claim as new and desire to secure by Letters Patent, is:—

1. The combination of a cylindrical platen and clamping means carried thereby and releasable at will, said clamping means comprising a rod contained within and extending longitudinally of the platen, one or more clamping fingers carried by said rod and extending through the platen to the outer surface thereof, means for supporting the 30 rod at one end in the platen so that the rod may swing with a pivotal movement around said point of support at one end of the platen and thus cause the clamping fingers to engage or release the sheet to be clamped 35 to the platen, and a finger piece carried by the platen and co-acting with said rod to control its pivotal movement.

2. The combination of a cylindrical platen and clamping means carried thereby and releasable at will, said clamping means comprising a rod contained within and extending longitudinally of the platen and supported at one end in a bearing opening in a head of the platen for pivotal movement, 45 and into which bearing opening the rod may be introduced by a longitudinal movement of the rod, one or more clamping fingers secured to said rod for bodily movement therewith and projecting from said rod through 50 openings in the platen to the outer side thereof, and hand controlled means carried by the platen and co-operative with the other end of the rod to control its movement into and out of clamping position.

60 3. The combination of a cylindrical platen, a rod contained in and extending longitudinally of the platen and supported at one end for pivotal movement, and a hand releasable lever carried by the platen and detachably 65 connected with said rod at the other or free

end thereof, and one or more clamping fingers carried by said rod and extending through openings in the platen to the outer surface thereof.

4. The combination of a cylindrical 70 plate, a platen head at one end thereof having a bearing opening, a rod contained within and extending longitudinally of the platen and introduced into said bearing opening by a longitudinal movement of the rod, a second platen head at the other end of the platen, a spring pressed lever carried by said second platen head and detachably connected with the other or free 75 end of said rod, and one or more clamping fingers fixed to said rod and extending through openings in the platen to the outer surface thereof.

5. The combination of a cylindrical 80 platen, a platen head at one end thereof having a bearing opening, a rod contained within and extending longitudinally of the platen and introduced into said bearing opening by a longitudinal movement of the rod and when seated in said opening adapted 85 to receive a pivotal movement around this point of support so that the opposite or free end of the rod may swing towards and away from the axis of the platen, a second platen head at the other end of the 90 platen, a spring pressed lever provided with a finger piece, said lever being mounted on the second platen head and detachably connected with the free end of said rod to control 95 its pivotal movement, and one or more clamping fingers carried by said rod and extending through openings in the platen to the outer side thereof, each of said clamping fingers having a bent-over engaging portion at its free end.

6. The combination of a cylindrical 100 platen, a platen head at one end thereof having a bearing opening, a rod contained within and extending longitudinally of the platen and introduced into said bearing opening by a longitudinal movement of the rod and when seated in said opening adapted 105 to receive a pivotal movement around this point of support so that the opposite or free end of the rod may swing towards and away from the axis of the platen, a second platen head at the other end of the platen, a spring pressed lever provided with a finger piece which extends outside of the platen at one end thereof 110 where it may be manipulated by the operator, said lever being pivoted on said second platen head and provided within the platen with a socket adapted to receive the other or free end of the rod and thus detachably connect the lever and rod so as to 115 control the swinging movement of the rod on the first mentioned platen head, and a series of clamping fingers fixed to said rod and projecting through openings in the 120

platens to the outer surface thereof, each clamping finger being bent at its free end portion to form an engaging member to co-act with the label or card to be clamped to the platen.

7. The combination of a cylindrical platen, a platen head having a tapering bearing opening, a rod contained within the platen and seated at one end in said bearing opening, hand controlled means carried by the platen and connected with the rod at the other end thereof, and one or more clamping fingers carried by said rod and extending through openings in the platen to the outer surface thereof.

8. The combination of a cylindrical platen, a platen head at one end thereof having a tapering bearing opening, a rod contained within the platen and extending longitudinally thereof and seated at one end in said bearing opening by a longitudinal movement of said rod, a second platen head at the other end of the platen, a lever pivoted on said second platen head and extending at one end into the platen where it is provided with means by which the lever may be detachably connected with the other or free end of said rod, the lever at its outer end extending outside of the platen where it is provided with a finger piece, clamping fingers fixed to said rod and projecting through openings in the platen to the outer surface thereof, and a spring co-acting with said lever and exerting its force through the lever on said rod to swing it in its bearing opening and cause the clamping fingers to engage the card or label and clamp it in position on the platen.

9. The combination of a cylindrical platen having a platen head at one end with a bearing opening, a clamping rod con-

tained within the platen and introduced at one end into said bearing opening by a longitudinal movement of the rod and when thus positioned adapted to swing laterally at its free end around the point of its support in the platen head, a second platen head at the other end of the platen, a hand controlled spring-pressed lever carried by said second platen head and having a socket adapted to receive the other or free end of said rod and to be detached therefrom by a detachment of the second head, and clamping fingers fixed to said rod and projecting through openings in the platen to the outer surface thereof and having bent-over engaging ends to clamp the card or label to the platen.

10. The combination with a platen, a line spacing wheel fixed thereto, clamping fingers carried by the platen and situated in a line extending longitudinally thereof between two adjacent teeth of the line spacing wheel, a laterally swinging rod contained within the platen to one side of the center thereof and to which said clamping fingers are fixedly secured and from which they project through openings in the platen to the outer surface thereof, and a spring pressed hand controlled controlling lever pivoted on and supported directly by a platen head and detachably connected with and supporting said rod at one end thereof to control the laterally swinging movement of said rod.

Signed at Syracuse, in the county of Onondaga, and State of New York, this 11th day of April A. D. 1923.

JOSEPH B. HOLDEN.
